(57) **CLAIM**

The ornamental design for a pendant, as shown and described.

DESCRIPTION

FIG. 1 is a front perspective view of a pendant showing my new design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof; and,

FIG. 8 is a front view of the pendant of FIGS. 1-7 showing a stone region in a changed state of appearance relative to FIGS. 1-7. The stippling shown on the stone region in FIG. 8 represents a contrast of appearance with respect to the remaining stones and the change of state is affected.

The broken lines in the drawings depict portions of the pendant that form no part of the claimed design.
